MOTORLESS TOY AIRPLANE

Frederick A. Christiansen, Los Angeles, Calif., assignor of two-thirds to William H. Hammer, Santa Monica, Calif., and one-third to Lane Rhodes, Santa Monica, Calif.

Application July 16, 1937, Serial No. 154,109

20 Claims. (Cl. 272—31)

This invention relates to a toy airplane apparatus driven by manually operated means.

An object of the invention is to provide a manually operated toy airplane which is exceedingly simple in construction, and which requires a less number of parts than toy airplanes of this general type that are adapted to fly about a central pylon and perform various stunts.

Another object of the invention is to regulate 10 by means of remote control manually operated means, the movement of the plane whereby to cause it to "wing over" or "barrel roll" by varying the speed of flight.

Another object of the invention is to provide in 15 a toy airplane of the type described, a novel mounting means for the plane so as to permit it to freely pivot about its longitudinal central axis, and to be quickly removed to allow replacement of another type of plane.

20 A still further object of the invention is to provide a toy airplane having wing surfaces which, during certain speeds of flight, cause the plane to "barrel roll" as it flies around a central pylon.

25 Other objects and advantages will appear hereinafter throughout the specification.

In the drawings:—

Figure 1 is an elevation of a device embodying 30 my invention showing the plane in flight;

Figure 2 is a vertical section of the structure shown in Figure 1, through substantially the center of the pylon;

Figure 3 is a horizontal section taken on the lines 3—3 of Figure 2 looking in a downward direction;

Figure 4 is a horizontal section taken on the lines 4—4 of Figure 3, looking in an upward direction;

Figure 5 is a plan view of the control means 40 showing its connection to the pylon;

Figure 6 is a bottom plan view of the tail surfaces of the plane, and showing the rod upon which the plane is mounted;

Figure 7 is a rear elevation of the airplane, 45 showing generally the parts illustrated in Figure 6;

Figure 8 is a central vertical section of the plane as shown on the lines 8—8 of Figure 6;

Figure 9 is a vertical section taken through the 50 right wing of the plane, as viewed in Figure 1;

Figure 10 is a vertical section taken through the left wing of the plane, as viewed in Figure 1, and

Figure 11 is a fragmentary plan view of one of the wing surfaces.

55 In the drawings, the numeral 1 indicates a py-

lon. Said pylon is detachably mounted on a base 2. The upper portion of the pylon is provided with a cap 3 through which extends a shaft 4. The sleeve 5, through which the shaft 4 extends, forms a bearing for said shaft to prevent wobbling of said shaft. The lower portion of the shaft 4 which may be termed the driven shaft, is hollow and is provided with a slot 6, communicating with the hollow interior of the shaft. Located below the shaft 4 is a driving shaft 7, the upper portion 8 of which extends within the shaft 4. The driving shaft 7 is provided with a pin 9 which projects into the slot so as to provide a driving connection between the shafts 7 and 4, that will allow the shaft 4 to slide on the shaft 7 as it is rotated thereby. This is due to the fact that the upper portion of the shaft 7 extends within the hollow lower end of the shaft 4, and the pin 9 engages the sides of the slots 6 and rotates the shaft 4 as the shaft 7 is rotated, by 20 means hereinafter described.

The base 2 is provided with a bearing 10 which houses the lower end of the driving shaft 7. Mounted on the shaft 7 is a beveled gear 11, which is splined or otherwise fixed to said shaft. 25 Also attached above the beveled gear is a worm 12 which drives a worm wheel 13, to which is attached a crank 14. The end of the crank 14 has pivotally attached thereto a rod 15 whose opposite end is pivotally attached to a yoke 16 which surrounds a sleeve 17 that is adjustably fixed by means of a screw 18 to the shaft 4. There is a second bearing 19 in the base 2 which houses the shaft 20 having mounted thereon the pinion 21, which is in meshed relation with the gear 11, 35 and which drives said gear. The middle portion of the shaft 7 is housed in a bearing 22 formed at the upper end of the supporting arm 23 mounted on the base 2. Said arm 23 also is provided with a bearing 24, Figure 3, which supports the 40 worm wheel 13 in such manner that it is always in proper meshed relation with the worm 12. The parts 12, 13, 14, 15 and 16 comprise an offset drive means for causing the plane 44 and its supporting arm 40 to have up and down movements. 45

Adjustably mounted upon the shaft 4 by means of the screw 25, is a collar 26, and surrounding the shaft 4 is an expandable coil spring 27 having its lower end bearing against the collar 26 and its upper end against an abutment 28 forming the 50 lower end of the bearing 5. Said spring tends to force the shaft 4 downwardly, to thereby counter-balance the weight of the plane and its support. Mounted on the cap 3 is a washer 29 having an aperture through which the shaft 4 extends. 55

The numeral 30 indicates a decorative globe-shaped member having a disk-like base 31 and an aperture 32, through which the shaft 4 extends. The upper end of the shaft 4 is provided 5 with a pivot 33. Pivots attached at the pivot 33 is an arm 34 which is supported by a second arm 35 having its upper end pivoted at 36 to said first named arm and attached by a pivot 37 to the disk-like base 31. The globe-shaped member 10 30 is provided with a slot 38, the arm 34 being adapted to move up and down in said slot, according to the position of the airplane now about to be described.

Detachably connected as by the cotter pin 39 15 is a rod 40 which extends within an aperture 41 in the arm 34. Said rod 40 is provided with an aperture, not shown, through which the cotter pin 39 extends. The opposite end of the rod 40 has a curved portion 42 and a right-angled rod 20 portion 43, which extends within the plane 44. Said airplane is provided with a propeller 45 which is freely pivoted at 46 so as to be driven by the air as the plane is turned about the pylon 1. Said propeller is not otherwise driven. The 25 numeral 47 indicates ground-engaging wheels mounted on struts 48. The plane 44 is detachably mounted on the right-angled portion 43 of the rod 40, as follows:

Said right-angled rod portion 43 is provided 30 with one or more collars 49 and the interior of the body of the plane is provided with at least two (only one being shown) bearings, similar to the bearing 50, which are provided with apertures 51 to allow the plane 44 to be mounted on the portion 43 or detached therefrom. It will be noted 35 that the plane may freely tilt about said portion 43 and is caused to automatically tilt by the means hereafter to be described. There is a spring 52, the left portion of which (Figure 6), is attached by glue or other suitable means to the 40 interior of the plane and which is adapted to bear against the collar 49, as shown in Figures 6, 7 and 8. By grasping the end 53 of the spring and pulling downwardly, as viewed in Figure 8, the spring may be released from the collar 49 so 45 as to allow the withdrawal of the plane from the rod portion 43, and the insertion of another plane of different type, in place thereof. There may be a number of planes provided of different 50 types, such as bombers, commercial planes, observation planes, etc.

The plane is provided with ailerons 54 and 55, the surfaces of which are illustrated in cross section in Figures 9 and 10 of the drawings. The 55 rear edges of the ailerons are preferably provided with clips 56 to hold in adjustment the rear edges of the wings which have been bent, as shown in Figures 9 and 10. The shape of these ailerons, as shown in these figures, causes the plane to 60 "barrel roll" as it flies around the pylon.

When the plane has attained proper speed by the means hereinafter to be described, the differently shaped surfaces of the ailerons will cause the plane to rotate about its central axis and cause the plane to "wing over" or "barrel roll".

The base 2 is provided with an aperture 57 into which is adapted to fit a pin 58, attached to a housing 59, the opposite end of which is provided with a bridge or cross-over 60 for the plane to 70 travel over when running on the ground. The runway 60 is also provided with a pin 61, which fits within an aperture in another housing member 62, the opposite end of which is provided with a pin 63 which fits within an aperture 64, of the control device 65. Said control device is pro-

vided with a disk 66 and a handle 67. The central portion of the disk 66 has a bearing sleeve 68 which extends within the aperture 69, of the control device, and attached to the sleeve 68 is a flexible driving shaft 70, which may be composed 5 of braided wire, and whose opposite end is drivingly connected to the shaft 20.

There may be as many housing members 59 and 62 as need be necessary, according to the length 10 of the flexible driving shaft 70.

Operation

Rotation of the disk 66 by the handle 67 causes the flexible driving shaft to rotate pinion 21, which drives the beveled gear 11, thereby rotating 15 shaft 7. Rotation of the shaft 7 causes the rotation of the shaft 4 and movement of the parts, including the globe 30, arm 34, rod 40, and plane 44 around a center defined by the axis of shafts 4 and 7. Rotation of said shaft 7 also causes 20 worm 12, and worm gear 13, to be rotated, and the up and down movement of the shaft 4 by means of the crank 14, rod 15, and yoke 16. It will be appreciated that the sleeve 17, being fixed to driven shaft 4, rotates with said shaft, and 25 that the yoke 16 does not rotate, but its engagement with the sleeve 17 causes the shaft 4 to move up and down as said yoke is so moved by the crank 14, and rod 15. The upward movement 30 of the shaft 14 is resisted by the spring 27, but said resistance is overcome by the movement of the parts 14, 15 and 16.

The principal function of the spring 27 is to counterbalance the weight of the plane, and its supporting parts, and relieve the gears 11 and 21, and 12 and 13, from the strain of supporting these parts. As said shaft 4 is reciprocated in a vertical direction, the rod 40 and the plane 44 supported thereby, are caused to be raised and lowered. These parts are preferably so adjusted 40 that the plane will rest on the ground when not in use. It will take-off and begin to ascend as its speed of rotation increases, about the pylon 1, when the handle 67 is turned. The plane will rise to the position shown in Figure 2, when rotated 45 by the handle 67. The plane 44, after having taken-off, will gradually rise and fall one or more times for each revolution of the plane about the central pylon. While this is taking place, the surfaces 54 and 55 of the ailerons of the plane, when sufficient speed has been reached, will 50 cause the plane to "barrel roll", or rotate on its central longitudinal axis. The plane, therefore, has three distinct movements: first, it moves in a circle about the pylon 1; second, it seeks elevation and approaches the ground in regular sequence, and third, it rotates about its longitudinal axis. These movements of the plane present an 55 interesting spectacle to a child, or other person operating the plane.

It will be further noted that all of the parts are simple and of sturdy construction, and that no comparatively expensive mechanism is employed, such as electric motors, and the driving parts therefor. It is also to be noted that foot operated means may be substituted for the hand operated means shown.

The foregoing description and drawings are understood to be for illustrative purposes only, and it is further understood that the invention 70 is adaptable to various modifications. I desire to be limited therefore in the practice of my invention only to the extent as defined by the appended claims. For instance, I may substitute for the driving connection between disk 66 and the 75

shaft 1, instead of the flexible wire drive, any other well known drive, such as a belt and pulley drive, or a rigid shaft drive, or a chain drive.

I claim:—

- 5 1. A toy airplane apparatus comprising a toy plane and including means for supporting and guiding the plane around a center, means for causing said plane to travel around said center, including driving and driven shafts, a slidable 10 driving connection between said shafts whereby said driven shaft may be rotated by said driving shaft and may slide in relation thereto, an arm mounted on said driven shaft, said plane being mounted on said arm, means driven by said 15 driving shaft and connected to said driven shaft for causing said driven shaft to slide with relation to said driving shaft and compel up and down movements of said plane, and manual means for causing said plane to move about said supporting and guiding means.
2. A toy airplane apparatus comprising a toy plane and including means for supporting and guiding the plane around a center, means for driving said plane around said center comprising 25 a flexible shaft, a driving and driven shaft, said driving and driven shafts being connected by a telescoping driving connection, means driven by said drive shaft for causing said driven shaft to slide with relation to said driving shaft and 30 compel said plane to have up and down movements while in flight, and said plane having surfaces to cause the same to roll on its central longitudinal axis when in flight.
3. A toy airplane apparatus comprising a toy 35 plane and including means for supporting and guiding the plane around a center, means for causing said plane to travel around said center, including driving and driven shafts, a slidable connection between said shafts whereby said 40 driven shaft may be rotated by said driving shaft, and may slide thereon, an arm mounted on said driven shaft, said plane being mounted on said arm, manual means for causing said plane to move about said supporting and guiding means, 45 and offset drive means connected to said driving and driven shafts for causing said plane to be raised and lowered as said plane moves around said center during flight.
4. A toy airplane apparatus comprising a toy 50 plane and including means for supporting and guiding the plane around a center, means for driving said plane around said center comprising driving and driven shafts, hand operated means for driving said shafts, and offset drive 55 means for causing said plane to be alternately raised and lowered as it moves around said center during flight.
5. A toy airplane apparatus comprising a toy 60 plane and including means for supporting and guiding the plane around a center, means for driving said plane around said center comprising driving and driven shafts, hand operated means for driving said shafts, means for causing 65 said plane to be raised and lowered as it moves around said center during flight, said raising and lowering means including a crank, means for driving said crank from said driving shaft, and a connection from said crank to said driven shaft.
- 70 6. A toy airplane apparatus comprising a toy plane and including means for supporting and guiding the plane around a center, means for moving said plane around said center including a control located remote from said center, hand operated means for operating said control, a

flexible drive shaft connected to said hand operating means, means connecting said flexible drive means to a driving shaft, a driven shaft having an aperture and a slot, one end of said driving shaft being adapted to extend within said aperture and having a pin extending within said slot, whereby to permit said driven shaft to slide relative to said driving shaft, means connected to said driving and driven shafts to cause said driven shaft to move in a vertical direction as 10 said driving shaft is rotated, and means connecting said plane to said driven shaft whereby said plane is raised and lowered as said shaft is moved in a vertical direction during the flight of said plane. 15

7. A toy airplane apparatus comprising a toy plane and including means for supporting and guiding the plane around a center, means for driving said plane around said center comprising driving and driven shafts, hand operated 20 means for driving said shafts, said plane supporting means including means on said plane to permit free rotation of said plane on its longitudinal axis, and additional means on said plane to cause the same to rotate on said longitudinal 25 axis when in flight.

8. A toy airplane apparatus comprising a toy plane and including means for supporting and guiding the plane around a center, hand operated means for driving said plane around said center, 30 said plane supporting means including supports on said plane permitting free turning movements of the same about its longitudinal axis, and additional means on said plane for causing the same to rotate on its longitudinal axis while in 35 flight.

9. A toy airplane apparatus comprising a toy plane and including means for supporting and guiding the plane around a center, means for driving said plane around said center, said plane 40 supporting means including supports on said plane permitting free turning movements of the same about its longitudinal axis, and additional means on said plane for causing the same to rotate on its longitudinal axis while in flight. 45

10. A toy airplane apparatus comprising a toy plane and including means for supporting and guiding the plane around a center, means for driving said plane around said center, said plane supporting means including supports on said 50 plane permitting free turning movements of the same about its longitudinal axis, and additional means on said plane for causing the same to rotate on its longitudinal axis while in flight, and means for detachably mounting said plane on 55 said supporting means.

11. A toy airplane apparatus comprising a toy plane and including means for supporting and guiding the plane around a center, means for driving said plane around said center, said plane 60 supporting means including supports on said plane permitting free turning movements of the same about its longitudinal axis, additional means on said plane for causing the same to rotate on its longitudinal axis while in flight, said 65 additional means on said plane comprising oppositely curved aileron surfaces.

12. A toy airplane apparatus comprising a toy plane and including means for supporting and guiding the plane around a center, means for 70 driving said plane around said center, said plane supporting means including supports on said plane permitting free turning movements of the same about its longitudinal axis, additional means on said plane for causing the same to ro- 75

- tate on its longitudinal axis while in flight, said additional means on said plane comprising oppositely curved aileron surfaces, and clips attached to said oppositely curved surfaces.
- 5 13. A toy airplane apparatus comprising a toy plane and including means for supporting and guiding the plane around a center, means for driving said plane around said center, said plane supporting means including a rod having a right-angled portion extending longitudinally of said plane, and a bearing member adjacent the rear of said plane into which said extension protrudes when said plane is mounted thereon.
14. A toy airplane apparatus comprising a toy plane and including means for supporting and guiding the plane around a center, means for driving said plane around said center, said plane supporting means including a rod having a right-angled portion extending longitudinally of said plane, and a bearing member adjacent the rear of said plane into which said extension protrudes when said plane is mounted thereon, a collar on said extension, and a spring mounted on said plane, said spring being adapted normally to cause said collar to remain in juxtaposed position to said bearing member, but when released permits said collar and bearing to be moved with relation to each other, whereby to permit removal of said plane from said supporting means.
- 30 15. A toy airplane apparatus comprising a toy plane and including means for supporting and guiding said plane around a center, said plane having oppositely inclined wing surfaces, and said supporting means including a pivotal longitudinal support for said plane whereby said plane wing surfaces will cause said plane to rotate on its longitudinal axis when in flight, and manually operated means for causing said plane to fly around said center, said last named means including means to cause said plane to have undulatory movements toward and from a supporting surface as the same flies around said center.
16. A toy airplane apparatus comprising a toy plane and including means for supporting and guiding said plane around a center, said plane having oppositely inclined wing surfaces, and said supporting means including a pivotal longitudinal support for said plane whereby said plane wing surfaces will cause said plane to rotate on its longitudinal axis when in flight, and means for causing said plane to fly around said center, said
- last named means including means to cause said plane to have undulatory movements toward and from a supporting surface as the same flies around said center.
17. A toy airplane apparatus comprising a toy plane and including means for supporting and guiding the plane around a center, hand operated means for driving said plane around said center, said plane supporting means including supports on said plane permitting free turning movements of the same about its longitudinal axis, and additional means on said plane for causing the same to rotate on its longitudinal axis while in flight, said additional means comprising ailerons with oppositely curved surfaces in transverse cross section to provide upwardly and downwardly extending trailing edges, and clips attached to said trailing edges to retain the same in the proper position of curvature.
18. A toy airplane apparatus comprising a toy plane and including means for supporting and guiding the plane around a center, means for driving said plane around said center, said plane supporting means including a rod having a right-angled portion extending longitudinally of said plane, and entering the rear thereof, and a bearing member in said plane through which said extension protrudes when said plane is mounted thereon to thereby support said plane on said extension.
- 30 19. A toy airplane apparatus comprising a toy plane and including means for supporting and guiding the plane around a center, means for driving said plane around said center comprising driving and driven shafts, hand operated means for driving said shafts, offset drive means for causing said plane to be raised and lowered as it moves around said center during flight, and means for relieving said offset drive means from strain.
- 40 20. A toy airplane apparatus comprising a toy plane and including means for supporting and guiding the plane around a center, means for driving said plane around said center comprising driving and driven shafts, hand operated means for driving said shafts, offset drive means for causing said plane to be raised and lowered as it moves around said center during flight, and spring means for relieving said offset drive means from strain.

50 FREDERICK A. CHRISTIANSEN.
